THERMOSTATIC CONTROL FOR AUXILIARY-AIR DEVICES

Application filed February 12, 1927. Serial No. 167,776.

This invention relates to auxiliary air supplying and mixing devices, such as are used with internal combustion motors, and refers more particularly to application Serial No. 5 122,411, filed by Gaston A. Brunelle, July 14, 1926.

One of the objects of this invention is to improve upon the device, described by above mentioned application, that will respond to engine speed and regulate the auxiliary air intake proportionally.

This invention is designed and constructed to accomplish this by admitting more air at high speed and cutting down the auxiliary air at low speed, thereby giving a better carbureting effect, which in turn means a more economical and efficient engine.

A particular advantage of the device resides in the fact that hot air is admitted as auxiliary air instead of cold air. This will cause a better mixture than cold air and will help to pick up and volatilize that raw gas that tends to accumulate in the low points in the manifold.

25 A further advantage is a thermal control unit that operates in connection with the auxiliary air intake port and regulates it according to the heat of the engine.

The combination of the auxiliary air intake port with the thermal control unit and the admission of preheated air into the intake manifold, furnishes a combination that is new and produces effects that are highly satisfactory in regard to economy and power.

35 It is observed from the foregoing that a resultant effect, coming from a combination of the speed of the engine, and the heat of the engine, is utilized to control the auxiliary pre-heated air admitted to the intake manifold.

It is to be understood that this auxiliary air is admitted to the intake manifold between the carburetor and the intake valves, and when so admitted augments the air content of the mixture and consequently rarefies

the mixture. This is desirable at certain engine speeds and heats and is automatically obtained by our invention.

The above advantages, together with any and all subsequent ones developed by the 50 description, constitute our invention which is disclosed by the accompanying drawings.

In the drawings:

Figure 1 shows the invention as applied to an engine;

Figure 2 shows a section on line 2—2 of Figure 1;

Figure 3 shows an enlarged section of the thermal control unit.

Referring now in detail to the drawings, 60 in which 1 represents the intake manifold of the engine and 2 the exhaust manifold. Surrounding 1 and 2 is a sheath like member 3, which is held to the engine 4 by the head bolt as at 5, and the manifold bolts, as at 5' and 5''. This sheath like member is shaped to form an oven opened at the lower side as at 7 to slip over the intake manifold. Mounted on the top side 8 of the member 3 is a chamber designated 9 in its entirety. Suitably connected at one end to the chamber 9 is a connection 10, the other end of which suitably joins the flanged member 11. In this case the connection used is tubing, but may be flexible as the occasion demands. 70

The flanged member 11 is interposed between the carburetor 12 and the intake manifold 1. It is found more convenient to introduce it as a flanged member, but it may also be brought into the intake manifold by 80 means of an opening in the walls of the manifold anywhere between the carburetor and the point where the manifold branches to go to the cylinder ports.

The thermal control unit generally designated 9 is composed of an upper plate 13 and a lower plate 14, which plate 14 is also the top plate of the heating oven. Flangedly connected as at 15 to the upper plate 13 is a sleeve 16, screw threaded at the bottom on the inside 85 90

to join plate 14 as at 17. This construction furnishes the casing. The top plate 13 is provided with an outlet opening 18, which is screw threaded as at 19 and takes a standard coupling 20, which in turn joins the aforementioned pipe 10.

Depending from plate 13 and below the opening 18 is provided a unit generally designated 21, which is screw threaded and joined to plate 13 as at 22. Contained within this unit is a valve member 23 shaped to fit into the seat 24, which seat is a part of the unit 21. An annular space 25 is provided by making the diameter of the valve stem 26 smaller than that of the opening 27 in the member 21. A flange 28 formed on the bottom of the stem 26 serves as a stop for the upward movement of the entire valve. Small protuberances 29 prevent the flange 28 from seating and permit air to pass up through the annular space 25, although the valve is fully lifted.

Provided within valve 23 is another valve 30 with a seat 31, cut in the valve 23 itself. This valve 30 is also provided with a stem 32, the diameter of which is less than that of the opening 33, providing a second annular space 34. Fixed to the lower end of the stem is a flange 35 which flange upon rising engages small protuberances 36 which hold it from sealing the annular air passage, thus providing a second additional air passage when both valve members are fully lifted by the suction from the cylinders.

In operation the larger valve lifts first, carrying with it the smaller valve inoperative. Upon increased demand for more air the smaller valve automatically rises, admitting air through the second annular space.

Depending from 21 is a hollow tubular member 37, provided with a flange 38. The flange 38 acts as a baffle for retarding the flow of air into the upper part of the sleeve 16.

Just above the flange 38 are provided openings 39 and 40 in the walls of the tubular member 37. Fixed to the bottom plate 14 is a thermal expansion unit generally designated 41, the design of which is more or less standard, and does not enter here except that it is provided with a top surface 42, which receives the full travel of the expansion. Attached to this plate substantially in the center is a screw threaded fixture 43 into which is screwed a pin 44 hollowed at the upper end as at 45.

Holes 46 and 47 are cut in the walls of the hollowed portion in such a manner as to coincide with holes 39 and 40 respectively. These holes 46 and 47 are larger in diameter than holes 39 and 40 and are so placed that a portion of the holes 39 and 46, also 40 and 47, coincide when the thermostat is cold and the larger diameter is to allow the thermostat a longer movement and still keep the holes in alignment. From this it is evident

that an opening always exists, but is small when the engine is cold, and fully opened when the engine is hot.

In Figure 3 is exemplified a condition where the thermostat has responded to heat and pushed the pin 44 up into the tubular member 37, until the holes 46 and 47 coincide with the holes 39 and 40 respectively, thereby fully opening an air passage to the interior of 37. The hot air then would rush in through openings 48 in the bottom plate 14, which is also the top of the oven, past the flange 38, which is a loose fit in the cylinder and acts as a baffle, and through the openings 39 and 40 on into the interior of the tubular member 37. From there it passes through the valves 23, and during high speeds of the engine also valve 30, and on through the connection 10 to the flange 11.

Provided in flange 11 is a baffle plate 49, which serves as a breaker. As the mixture composed of finely divided gasoline globules carried in suspension is swept along the manifold tube, and as the auxiliary air is admitted to this stream just in front of this baffle plate it is easy to conceive that a much better mixture is obtained by causing a disturbance at the point where the air is admitted. It not only causes the mixture to become more rarefied, but it tends to make a more uniform mixture since the globules are broken into more minute parts and the new air is thoroughly stirred in by the disturbance.

The accompanying drawings show one embodiment of our invention and since it is possible to apply it in various ways we understand we are entitled to such modifications and variations as do not depart from the scope of the description and appended claims.

We claim:

1. A device of the type described, comprising in combination an exhaust pipe, a heating oven surrounding said pipe, means disposed at the top of said oven for receiving heated air from the oven, an intake manifold, communications between said means and said manifold for conveying heated air to said manifold, said manifold having a large opening for receiving the heated air, and a baffle plate disposed adjacent to said opening and on the side nearest the engine intake ports, and extending part way into the manifold.

2. A temperature controlled suction-actuated air inlet device comprising an oven for enclosing the exhaust pipe of an engine, a chamber for receiving heated air from the oven, a thermostat mounted in said chamber and affected by the heated air, a conduit for carrying the heated air from the oven to the intake manifold, and a valve actuated by said thermostat for permitting a greater quantity of heated air to enter said conduit as the temperature of the air increases.

3. A temperature controlled suction actuated air inlet device, comprising a chamber for receiving heated air, and having air receiving openings, a baffle placed in said chamber, an outlet pipe having openings for receiving the air after it has passed the baffle, and a thermostat controlled by the heated air for regulating the amount of air entering the pipe.
